Primary Examiner—Ruth McInroy**[57] CLAIM**

The ornamental design for combined lighting and signalling device for helmet, as shown.

DESCRIPTION

FIG. 1 is a rear perspective view of a combined lighting and signalling device for helmet showing my new design;

FIG. 2 is a front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.
